UNITED STATES PATENT OFFICE.

FREDERIC E. FARWELL, OF FITCHBURG, MASSACHUSETTS.

GAGE FOR SAW-BENCHES.

SPECIFICATION forming part of Letters Patent No. 378,924, dated March 6, 1888.

Application filed November 3, 1887. Serial No. 254,187. (No model.)

To all whom it may concern:

Be it known that I, FREDERIC E. FARWELL, of Fitchburg, in the county of Worcester, State of Massachusetts, have invented a certain new and useful Improvement in Gages for Saw-Benches, of which the following is a description sufficiently full, clear, and exact to enable any person skilled in the art or science to which said invention appertains to make and use the same, reference being had to the accompanying drawings, forming part of this specification, in which—

Figure 1 is an isometrical perspective view of my improved gage detached from the saw-bench; Fig. 2, a vertical transverse section of the same enlarged, some of the parts being shown in side elevation; and Fig. 3, an end elevation.

Like letters and figures of reference indicate corresponding parts in the different figures of the drawings.

My invention relates more especially to that class of gages which are used in circular-saw and planing-machine benches for sawing or planing beveled work; and it consists in a novel construction and arrangement of parts, as hereinafter more fully set forth and claimed, the object being to produce a more effective and otherwise desirable device of this character than is now in ordinary use.

The nature and operation of the improvement will be readily understood by all conversant with such matters from the following explanation:

35 In the drawings, A represents the body of the rest, and B the guide-plate.

The body A is secured to the bench (not shown) by a tongue-and-grooved plate, z, and rendered adjustable thereon by means of a 40 screw and nut, v, in the ordinary manner. The forward edge of the body is provided with an upwardly-projecting vertical flange, m, and its ends with like flanges, k, the outer faces of the end flanges being grooved, as shown at g, 45 to receive plates h, which are fitted to slide loosely therein, the forward end of said flanges being provided with projections i, which serve as stops for the guide-plate.

The guide B consists of a horizontally-arranged metallic plate which is hinged at its upper edge to the outer ends of bars d, as shown

at t, and at its lower edge to the outer ends of the plates h, as shown at r. The plates h are provided with elongated curved slots w, and the inner ends of the bars d pivoted to said body by means of bolts l, which pass through said slots into the flanges k. The lower edge of the guide B is beveled inwardly, as shown at b, where it rests on the bench. One end of a rod, D, is pivoted by means of a bolt, q, in ears a on the inner face of the guide B. The opposite end of the rod D is screw-threaded at f and provided with a nut, C, said nut being provided with a hand-wheel, K, at its outer end and journaled in a sleeve, G, which is pivoted on the bolt y in vertical standards H, centrally secured to the rear of the body A, said nut being so constructed and arranged as to rotate in said sleeve, but not withdrawn therefrom.

In the use of my improvement the gage is fixed at the required distance from the saw and secured by means of the bolt and nut. By turning the hand-wheel K to the right or left and causing the screw D to advance or recede the lower edge of the guide B will be forced outward or inward, as the case may be, until said guide is adjusted to any desired angle. The board or other article is then held against the face of the guide and fed to the saw in the usual manner. As the screw D recedes, each of the arms d is moved through the arc of a circle of which the pivot l is the center, the lower side or edge of the guide B being at the same time drawn toward the flange m and the outer ends of the plates h raised and moved toward the bolts l. To compensate for this compound movement of the parts, the slots w in the plates h are curved to correspond with the curvature of the arc described by the upper ends of the bars d, and thereby prevent said plates from cramping on the bolts l, the grooves g in the flanges k being of such width as to permit free vertical vibratory movements of said plates. By withdrawing the rod D until the lower edge of the guide-plate strikes the flange m the guide will assume a vertical position, as shown by the dotted lines in Fig. 3, and can then be used for cutting straight or square work, if desired.

Having thus explained my invention, what I claim is—

1. In a gage of the character described, the body A, provided with the flanges *m* *k* and stops *i*, the guide B, having the beveled edge *b*, the arms *d*, pivoted at their outer ends to the upper portion of the guide B and at their inner ends to the flanges *k*, the plates *h*, provided with the slots *w* and pivoted at their outer ends to the lower portion of the guide B, the sleeve G, pivoted in the standard H, the screw-threaded shaft D, provided with the nut C and jointed to the guide B, and the nut and screw *v*, all constructed, combined, and arranged to operate substantially as described.

2. In a gage of the character described, the guide B, and the plates *h*, pivoted to the guide B 15 and provided with the curved slots *w*, in combination with the bolts *l*, flanges *k*, body A, pivoted arms *d*, and a screw for moving said guide back and forth, substantially as set forth.

FREDERIC E. FARWELL.
